UNITED STATES PATENT OFFICE.

ALBERT PREISS, OF NORWOOD, SOUTH AUSTRALIA.

RAILWAY-JOINT.

SPECIFICATION forming part of Letters Patent No. 448,257, dated March 17, 1891.

Application filed March 18, 1890. Serial No. 344,333. (No model.)

To all whom it may concern:

Be it known that I, ALBERT PREISS, plumber, of Norwood, in the Province of South Australia, have invented an Improved Joint for the Rails of Railways or Tramways, of which the following is a full, clear, and exact description.

My invention relates to an improved construction of the rails of railways or tramways, and is intended to take the place of the fish-plates and bolts used for such purpose.

The special feature of my invention consists in constructing the joints of rails in such way as to form a bed or socket in which the ends of the rails rest and into which they are clamped by a fish-plate or side piece kept in position by a key screwed into the sleeper. I also cut the ends of the rails at an angle, say, of forty-five degrees, instead of at a right angle, so that they may meet diagonally and overlap one another. While permitting free longitudinal contraction or expansion, my improved joint will not allow of lateral motion or rising, and by providing a solid bed on which the ends of the rails rest entirely obviates the dropping or sinking, which renders constant packing necessary when the ordinary fish-plates and bolts are employed. By cutting the ends of the rails at an angle the wheels of the rolling-stock in crossing the joint rest on both rails at once, and since my improved joint will not allow the end of either rail to rise the edges or corners are not injured, as is the case with the joint at present in use.

My improved rail-joint may be constructed of iron or steel, and may be rolled or pressed or partly rolled and partly pressed.

In order that my invention may be better understood, I will now proceed to describe the same by reference to the accompanying drawings, in which—

Figure I is a plan of rails and joint complete; Fig. II, a side elevation of the same; Fig. III, a sectional elevation of rail-joint

fish-plate or side piece and key; Fig. IV, a plan and elevation of the ends of the rails, showing the diagonal cut.

Similar letters refer to similar parts in all figures.

A is a rail of any size, (in the present instance a full-sized section of a forty-one-pound steel rail is shown;) A', diagonal cut ends of rails; B, a rail-joint having a solid bed and provided with projecting lugs B' B³ 55 and a keel or projecting piece B². The lug B' projects inward and is of sufficient length to engage the corner where the head of the rail joins the web. The keel or projecting piece B² runs longitudinally the whole length 60 of the joint and projects downward at right angles to the bed-plate into a groove cut for the purpose in the sleeper. The lug B³ projects upward at right angles to the bed-plate of the joint B, a space being allowed between 65 the lug B³ and B' corresponding to the foot of the rail A.

G is a fish-plate or side piece of angle iron or steel and having sides of sufficient length to take a bearing underneath the head of the 70 rail and against the inner side of the lug B³.

D is a sleeper of permanent way.

E is a key provided with suitable screw-thread and having a head of such length as to engage the fish-plate or angle side piece C. 75

I wish it to be understood that I do not confine myself to the special form of lug B', but may make it to fit the web and foot of the rail or may cause it to project at right angles to the bed-plate in a similar manner to B³ 80 and provide a second fish-plate on side piece C. The bed-plate may also, if found desirable, be constructed without the projecting piece B².

It will be seen by reference to Fig. III that 85 the bed-plate of the joint is let into the sleeper in order that the foot of the rail may rest on a level with the face of the former.

In cutting the ends of the rails diagonally I do not confine myself to an angle of forty- 90

five degrees, but may vary the angle according to the size or class of the rail employed.

Having now particularly described and explained the nature of my said invention and in what manner the same is to be performed, I declare that what I claim is—

In a rail-joint, the combination, with the bed-plate having projecting lugs, one of which projects inward so as to engage the head and web of the rail, of a fish-plate or angle-piece

and a screwed spike having its head extending at right angles to the screw-threaded part and adapted to be turned so as to be pressed against said fish-plate, substantially as and for the purpose specified.

In witness whereof I have hereunto set my hand in presence of two witnesses.

ALBERT PREISS.
